UNITED STATES PATENT OFFICE.

NORAH HANSON, OF SHARON, NORTH DAKOTA.

DESIGN FOR A HERO SERVICE PIN, BADGE, OR SIMILAR ARTICLE.

55,270.

Specification for Design.

Patented May 25, 1920.

Application filed February 25, 1919. Serial No. 279,193. Term of patent 3½ years.

To all whom it may concern:

Be it known that I, NORAH HANSON, a citizen of the United States, residing at Sharon, in the county of Steele and State of North Dakota, have invented a new, original, and ornamental Design for a Hero Service Pin, Badge, or Similar Article, of which the following is a specification, the accompanying drawing forming a part thereof.

The figure is a plan view of a pin, badge or similar article showing my new design.

The design consists of a black rectangular field, surrounded by a border of gold or yellow, with a gold or yellow star in the field, gold or yellow letters "U" and "S" in said field at the opposite sides of the star near the ends of the field, and a gold or yellow letter "H" below the star.

I claim:

The ornamental design for a pin, badge, or similar article, as shown and described.

NORAH HANSON.
